MINING MACHINE.

Application filed December 26, 1923. Serial No. 682,691.

The invention relates to mining machines, and more particularly to novel and useful machines for cutting a kerf at variable heights in the vein.

5 Objects and advantages of the invention will be set forth in part hereinafter and in part will be obvious herefrom, or may be learned by practice with the invention, the same being realized and attained by means 10 of the instrumentalities and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain 20 the principles of the invention.

Of the drawings:—

Fig. 1 is a top plan, with parts omitted and other parts broken away, of a machine constructed in accordance with my invention;

25 Fig. 2 is a side elevation, corresponding to Fig. 1;

Fig. 3 is a transverse vertical section, on an enlarged scale, taken substantially on the line 3—3 of Fig. 1;

30 Fig. 4 is a central, longitudinal, vertical section on an enlarged scale, taken substantially on the line 4—4 of Fig. 1;

Fig. 5 is a transverse vertical, partial section taken on the line 5—5 of Fig. 4;

35 Fig. 6 is a fragmentary, enlarged, sectional detail taken on the line 6—6 of Fig. 4;

Fig. 7 is a fragmentary enlarged sectional detail taken on the line 7—7 of Fig. 1;

40 Fig. 8 is a diagrammatic view showing the mechanism arranged to cut a kerf at an intermediate point in the vein;

Fig. 9 is a similar view showing the mechanism arranged to cut a kerf at a higher level in, or at the top of, the vein;

45 Figs. 10, 11 and 12 are similar diagrammatic views, showing the mechanism arranged to cut inclined kerfs at both the front and side of the machine;

Fig. 13 is a fragmentary section on line 50 13—13 of Fig. 6;

Figs. 14 and 15 are fragmentary plans, corresponding to the lower left-hand corner of Fig. 1, showing the use of ordinary trac-

tion and flanged wheels instead of the belt traction treads; and

55 Figs. 16 and 17 are diagrammatic views, similar to Figs. 8 to 12, showing different positions of the cutter.

The invention is directed primarily to producing a mining machine which has a wide 60 range of adaptability for cutting kerfs at relatively widely varying points or levels; which is of very low and compact construction, and thus adapted for work in very thin seams, while being also well adapted for 65 work in much thicker seams, the range or adaptability of a particular machine in this respect being very great.

The invention is further directed to producing a machine having the functions and 70 capacities mentioned, which is automotive, and, if desired, controllable from a relatively distant point, both as to the travel of the machine and the operation of the kerf-cutting mechanism.

75 The invention is likewise directed to providing a machine which is of great efficiency, of very simple but exceedingly sturdy design and construction, and of relatively very light weight.

80 Referring generally to the main structural features of the present preferred embodiment, a main frame is provided, having preferably automotive traction means, comprising an endless traction tread at either side of the machine, operable together or independently, to travel and to maneuver the machine, the treads being driven by a motor and the action controlled by interposed clutch mechanisms.

85 The preferred form of kerf cutter herewith embodied is a bar cutter carrying an endless cutter chain, provided with a motor adapted to drive the chain about the bar and to travel the bar relatively to the machine in a circular path. The cutter bar and its motor are mounted upon a support or platform with which cooperate suitable means to raise and lower the cutter bar and preferably its motor to vary the height or level of the kerf in the 90 coal vein.

95 In accordance with one feature of the invention, and with a view to providing a powerful, simple and light machine, this raising and lowering of the cutter bar and 100 preferably its motor therewith, is effected

by utilizing a part of the traction means and devices cooperating therewith; although this is not essential so far as concerns certain other features of the invention.

5 Other objects and advantages, and other features, of the invention will be pointed out in connection with the detailed description; and it will be understood that the foregoing general description and the following detailed description are exemplary and explanatory but are not restrictive of the invention.

10 Referring now in detail to the present preferred embodiment, a general frame 1 is provided having longitudinally-extending side reaches 2 and 3 and horizontally-extending cross reaches 4 at the front and 5 near the rear. There are also provided internal or intermediate longitudinally-disposed frame members 6 and 7, fixed to, and extending 15 from, the cross frame member 4 at the front to the cross frame member 5 at the rear, these frame members being preferably bent downwardly medianly to accommodate and support certain parts of the mechanism, as will 20 appear from the drawings.

25 In the embodied form of automotive and dirigible traction means, an endless traction tread belt 15 extends longitudinally at one side of the machine, and a corresponding endless traction tread belt 16 extends along the other side of the machine. The traction belt 16 is omitted from Fig. 1 for the sake of clearness in showing certain parts of the mechanism.

30 35 In accordance with certain features of the invention, as already indicated, the embodied means for raising and lowering the kerf cutting bar utilizes certain of the traction devices, and accordingly these mechanisms will be described together, although it will be understood that they may be constructed separately so far as concerns certain features of the invention.

40 45 The embodied form of driving and holding means for the endless traction tread belts 15 and 16 comprise flanged, broad-faced sprocket wheels 17 and 18, respectively, provided with peripheral, centrally located sprocket teeth 19 and 20, and fixed 50 on shafts 21 and 22. These sprocket wheel shafts are journaled, respectively, in correspondingly yoked arms 23, 24 and 25, 26. These pairs of arms are integral with corresponding internally-apertured hubs 27 and 28, which are loosely mounted on, and near the ends of, a cross shaft 29, supported at its ends in bearings 30 and 31, carried upon the frame members 2 and 3, respectively.

55 60 Oppositely extending from the arms 23 and 24, and likewise integral with the hub 27, are a pair of arms 39 and 40 in the outer ends of which is journaled loosely a broad-faced flanged wheel 41, the shaft 42 thereof being mounted in the arms. In like manner, on the other side of the machine, arms

44 and 45 extend oppositely from the arms 25 and 26 and are formed integral with the internally-apertured hub 31. A similar flanged wheel 46 is mounted freely upon a shaft 47 carried in the ends of the arms 44 and 45.

65 In the embodied form, a generally similar mechanism is provided at the opposite end of each of the endless traction treads except that the pair of wheels for each of the treads 70 have no sprocket teeth or driving means. For the tread 15, a double yoke is provided having an internally apertured hub 51, loosely mounted on transversely extending shaft 52, supported at its ends, respectively, in bearings 53 and 54 mounted on the side frame members 2 and 3. The hub 51 has a pair of forwardly-extending yoke arms 55 and 56, in which is mounted a shaft 57. Upon shaft 57 is rotatively carried a broad-faced flanged wheel 59, upon which the endless traction tread runs.

75 80 Likewise there are a pair of rearwardly-extending yoke arms 65 and 66, integral with the hub 51, and having a shaft 67 mounted in the outer ends thereof, upon which is rotatively carried a broad-faced, flanged wheel 69. At the opposite side of the machine is a similar mechanism, comprising a hub 70, loosely journaled on the shaft 52, and having a pair of forwardly-extending yoke arms 71 and 72.

85 90 95 Mounted in the outer ends of these arms is a shaft 73, upon which is rotatively mounted a broad-faced, flanged wheel 74, upon which the inner face of the endless traction tread runs.

100 105 110 Extending rearwardly from, and integral with, the sleeve 70, are a pair of yoke arms 79 and 80, carrying in their outer ends a shaft 81, upon which is rotatively mounted a broad-faced flanged wheel 82. The inner faces of the respective endless traction treads 15 and 16 run upon and are guided by all of the flanged wheels, and are driven respectively by the sprocket wheels 17 and 18.

115 120 125 In the preferred and illustrated embodiment, the kerf cutter and its driving motor are mounted upon what I conveniently term an auxiliary frame or support. As embodied, this support comprises longitudinally-extending side frame members 100 and 101 (Figs. 1, 4 and 5). Near their rear ends, the frame members 100 and 101 are connected together by a cross frame member 102. Forwardly of this, and likewise constituting a part of the motor mounting, is a cross frame member 103. Farther forwardly are two downwardly-extending frame members 104 and 105, connected together at their bottom ends by a cross frame member 106. The particular form of mounting for the motor and cutter bar upon this structure will be later described in detail.

130 The auxiliary frame or support is mounted

on the general frame so as to be raised or lowered thereby and to be kept in its proper relative position, but at the same time it is free to have relative angular movement, so that the position and also the angle of the kerf may be varied as desired relatively to the surface, upon which the traction treads rest.

For this purpose each end of the frame member 101 has a ball and slot connection with the yoke arms 44 and 79. In the embodied form of this connection, a lug 117 extends upwardly from the yoke arms 44 and 79, respectively, and a pin 118, mounted in the lug 117, has a ball head 119 which fits rotatively and slidably in a slot 122 formed in a block 120, fixed to the frame member 101. A retaining plate 121 may be used to keep the parts in position.

At the opposite side of the auxiliary frame or support, the frame member 100 has a longitudinally and transversely sliding support upon each of the yoke arms 40 and 66. In the preferred embodiment, a lug 126 is fixed to, and extends upwardly from, the yoke arms, and carries a pin 127 upon which is mounted a friction roller 128. A rounded contact block 129 is fixed to the underside of the frame member 100, and rests slidingly and rockingly upon the friction roller 128.

For the purpose of maintaining the auxiliary support in its proper relative place while permitting the raising and lowering and inclining thereof, the preferred embodiment comprises a bar 131 has at one end a pivot connection 132 with frame member 106 of the auxiliary support, and at its other end bar 131 has a ball and socket connection 133 mounted on cross frame plate 130. This holds the auxiliary support in place longitudinally of the machine while permitting the raising, lowering and inclination thereof. The arc through which bar 131 moves is so small that it is mechanically negligible.

In Fig. 14 the use of broad tread wheels 17^a and in Fig. 15 flanged wheels 17^b, are shown, in place of the endless belt traction treads. In this case the second wheel of each pair near each corner of the machine is omitted. The general construction and operation is otherwise substantially the same or similar. Figs. 16 and 17 show diagrammatically certain positions of these forms of the mechanism.

Means are provided by the invention for selectively imparting angular movement to any or all of the four yokes carrying the tread-engaging wheels in either one direction or the other about their shafts 29 and 52, to raise or lower the auxiliary frame or support, or to tilt it either forwardly or backwardly or transversely either to the right or to the left, or to effect a combination of these movements, as may be found desirable or necessary in determining the height and

direction or inclination of the kerf to be cut.

Some of the various positions are diagrammatically shown in Figs. 8 to 12. In Fig. 8 all of the traction tread engaging wheels are shown on the level, with the kerf cutter at 70 its lowest point. In Fig. 9 the wheel carrying yokes are shown swung from a substantially horizontal to a substantially vertical position thereby raising the kerf cutter to its highest operating level. It will be seen that by reason of each pair of traction tread engaging wheels at each end of each traction tread swinging symmetrically about its pivot mounting upon the sleeve of its yoke to effect the desired changes in the height or direction of the kerf cutter, the length of the traction tread is substantially unchanged. Merely the length of the tread engaging the ground or floor is modified by this movement of the mechanism.

In Fig. 10 the positioning of the two rear yokes to provide a downwardly inclined kerf cut at the front of the machine is shown. Correspondingly, in Fig. 11, similar positioning of the forward pair of yokes and tread-engaging wheels is shown to provide an upwardly inclined kerf at the front of the machine. In Fig. 12 the operation of the two yokes at one side of the machine, the wheels thereof engaging the ends of the same tread is shown, to provide an inclined kerf when the cutter bar is extending outwardly at one side of the machine.

Referring now to the power driven mechanism for selectively actuating the respective yokes and their tread-engaging flanged wheels, a platform 140 is mounted at the rear of the machine upon the ends of the frame members 2 and 3, and upon the frame member 5. At the same time the platform serves as a stiffening and strengthening brace for the frame. Upon this platform is mounted a motor 141, having its shaft 142 journaled in bearings 143 and 144 carried upon the platform 140. A worm 145 is fixed on shaft 142, and meshing therewith is a worm wheel 146, fixed on a shaft 147, journaled in bearings 148 and 149 integral with bearing 144. (Figs. 1, 2 and 3.)

At its opposite end, shaft 147 is journaled in bearings 153 and 154, formed on a housing 155. A worm 156 is fixed on shaft 147, and meshes with a worm wheel 157. Worm wheel 157 is fixed on a vertically-disposed shaft 158, journaled in and supported by the horizontal top of housing 155. Fixed also on shaft 158 is a bevel gear 159, which meshes with two beveled gear wheels 160 and 161, which are mounted loosely on shaft 162. Shaft 162 is journaled near its ends in bearings 163 and 164 carried on plate 140.

Bevel gears 160 and 161 are provided on their hubs with clutch jaws 165 and 166, respectively, with which cooperate a sliding clutch 167, which is splined upon shaft 162.

- Sliding clutch member 167 is operated in any suitable manner, as by a lever 171 engaging with an annular groove 172 in the clutch member. As the clutch member 167 is slid 5 into engagement alternatively with either of the bevel gears 160 or 161, the shaft 162 will be driven in either one direction or the other from the shaft 147, through the bevel gear 159.
- 10 The further mechanism for actuating the various yokes carrying the traction tread engaging wheels comprise connections from shaft 162 to either side of the machine. On the right side is a bevel gear 211, fixed on 15 one end of shaft 162. Gear 211 meshes with a bevel gear 212, fixed on a shaft 213, which is journaled in bearings 214, 215, 216 and 217 mounted upon the machine frame.
- To operate the lower left-hand yoke in 20 Fig. 1, as embodied, a pinion 223 is fixed on shaft 213, and meshes with a pinion 224, rotating loosely on shaft 225, which shaft is journaled in bearings in the members 30 and 217. Mounted on shaft 225, to slide there- 25 along but rotating therewith, is a clutch jaw 229, cooperating with a similar jaw formed on the pinion 224. Fixed on shaft 225 is a worm 230, meshing with a worm wheel 231. Wheel 231 is keyed on a sleeve which is an 30 extension of the hub 27, and which likewise encircles the shaft 29. Thus through the connections just described, and through opera- 35 tion of the clutch members 167 and 229, the motor 141 will swing the yoke 30 and its wheels 24 and 41 from the position of Fig. 8 to a variety of selected angular positions, two of which are exemplarily illustrated in Figs. 9 and 10.
- Further describing the embodied form of 40 connections for operating the yoke and tread-engaging wheels at the lower right-hand end of Fig. 1, a pinion 251 is fixed on shaft 213 and meshes with a pinion 252, loosely mounted on a shaft 253, which is journaled in bearings 45 in the members 53 and 217. A clutch jaw 254 is slideable along but rotatable with shaft 253, and engages with a corresponding clutch jaw on the pinion 252.
- A worm 256 is fixed on shaft 253 and meshes 50 with a worm wheel 257, the construction being similar to, or the same as, that shown at the left-hand end of Fig. 3 and already described. This mechanism, through clutch 167 and clutch 254, will operate the yoke member 55 and its tread-engaging wheels 59 and 69 in the manner already described for the corresponding mechanism at the other end of the tread 15. Two positions of this mechanism are shown in Figs. 9 and 11.
- On the opposite side of the machine the 60 selectively actuated means for determining the level of the kerf are similar in construction, and are connected to the other end of shaft 162. These comprise a beveled gear wheel 270, fixed on the end of shaft 162, and mesh- 65 ing therewith is a bevel gear wheel 271, which is fixed on the end of a shaft 272, carried in bearings 273, 274, 275 and 276. Fixed on shaft 272 is a pinion 277, which meshes with a pinion 278, mounted loosely on a shaft 279, 70 journaled in bearings in the members 31 and 276. A clutch 280 is slideable along, but rotatable with shaft 279. Fixed on shaft 279 is a worm 281, which meshes with a worm-wheel 282, which is keyed on a hub extension 75 of the yoke hub 28.
- The controlling mechanism for the right-hand upper mechanism in Fig. 1 comprises a pinion 310, fixed on shaft 272, and meshing with a pinion 311, which is loosely mounted 80 on a shaft 312, journaled in bearings 54 and 276. A clutch member 313 is rotatable with, but slideable along, shaft 312 into and out of engagement with a cooperating clutch member on the hub of pinion 311. Fixed also on shaft 312 is a worm 314, meshing with a worm wheel 315, fixed on an extension of the hub 70 of the yoke.
- It will thus be seen that through clutch 167 and clutch 280, the actuation and positioning 90 of the tread engaging wheels at the left-hand upper end of Fig. 1 may be effected in the manner already described. Likewise through clutch member 167 and clutch member 313, the actuation and positioning of the tread- 95 engaging wheels at the upper right-hand corner of Fig. 1 may be effected. By the selective operation of these four different mechanisms, the auxiliary frame or support which carries the cutter bar may be raised or lowered 100 at each corner thereof, and may be raised or lowered in a horizontal position or may be tilted in any direction desired, to position the kerf cutting bar at various desired angles as the exigencies of the work may require. 105
- In the embodied form of means for driving the endless traction treads, mechanism is provided for driving either or both treads forwardly or backwardly at various speeds. As so embodied, a broad-faced pinion 321 is fixed 110 on shaft 142, and meshing therewith, and slideable therewith, is a pinion 322, loosely mounted on a shaft 323, which shaft is supported in bearings 324 and 325 upon the machine frame. Fixed to the gear wheel 322 to rotate 115 with, and to slide therewith along shaft 323, is a pinion 329, which meshes with a gear wheel 330 for one of the drives of the machine, which is preferably the slow speed forward drive.
- Fixed also to the gear wheel 322 to rotate therewith, and to slide therewith along shaft 323, is a gear wheel 333. This gear wheel 333 is adapted to slide into mesh with a pinion 334 when pinion 329 slides out of mesh with the gear wheel 330. This sliding action is imparted to gear wheels 322, 329 and 333 by suitable means, such as an actuating lever 337. Gear wheels 330 and 334, which are 120 integral or otherwise fixed to rotate together, 130

are fixed on a shaft, journaled in bearings 338 and 339, which are part of the housing 340.

Fixed to the same shaft, to rotate with gear wheels 330 and 334, is a beveled pinion 345. 5 Meshing with pinion 345, at opposite sides thereof, are beveled gears 346 and 347, which are loosely mounted on a shaft 348, which shaft is journaled in bearings 349, 350, 351 and 352 the latter being mounted on frame plate 130. 10 Mounted to slide on shaft 348 and to rotate therewith, is a clutch member 353, adapted to be slid alternatively into engagement with beveled gear wheel 346 or gear wheel 347, so as to rotate shaft 348 in either 15 direction. An operating lever 359 is provided to actuate the clutch.

Shaft 348 at its opposite end has fixed thereto a worm 360 (Figs. 1 and 3), which meshes with a worm wheel 361, fixed on shaft 20 29. The connections therefrom for driving sprocket wheel 17, and thereby the tread 15, comprise a clutch member 362, mounted upon shaft 29 to slide therealong and to rotate therewith. An actuating lever 363 is provided 25 for the clutch member. Clutch member 362 is adapted to pass into and out of engagement with a cooperating clutch jaw fixed on the shaft of a sprocket wheel 364, loosely mounted on the shaft 29. A sprocket chain 365 runs over the sprocket wheel 364 and also over a sprocket wheel 366, which is fixed to the shaft 21 of the sprocket wheel 17.

On the opposite side of the machine are the 30 selective connections for driving tread 16, and these comprise a clutch member 371, slideable along but rotatable with shaft 29. Clutch member 371 is movable into and out of engagement with a cooperating clutch jaw, formed on the hub of a sprocket wheel 372, which wheel is loosely mounted on the shaft 29. A lever 373 is provided to throw clutch 35 371 in and out. A sprocket chain 375 runs over sprocket wheel 372 and over a sprocket wheel 376, which is fixed to the shaft 45 22 of the sprocket wheel 18, and thereby serves to drive the tread 16.

It will be seen that through reversing clutch 353 and clutch 362, tread 15 may be driven in either direction. Likewise through 50 reversing clutch 353 and clutch member 371, tread 16 may be driven in either direction, and the two treads may be driven simultaneously or separately, and thereby the machine may be traveled either forwardly or backwardly or wheeled to the right or to the left.

Referring now to the embodied form of mechanism for traveling the cutter bar relatively to the machine, in the present embodiment, this travel is in an arcuate path, and the kerf cutting mechanism and its motor are mounted upon and are movable together relatively to the auxiliary frame or support. 55 As embodied, a motor casing 399 (Figs. 1, 4 and 5) is provided with vertically-disposed top and bottom trunnions 400 and 401, respec-

tively. The bottom trunnion turns in a bearing in a plate 402, fixed upon the frame member 106. The top trunnion 400 turns in a bearing in a plate 403, carried by two rearwardly, outwardly and downwardly extending arms 407 70 and 408. Arms 407 and 408, at their top ends, are fixed to bearing block 403, and at their bottom ends they are fixed to the structure of the auxiliary frame or support.

A semi-circular, horizontally-disposed, internally-geared plate 411 is fixed upon the auxiliary frame, and meshing therewith is a driving pinion 412, which is fixed upon a shaft 413 and is rotatively supported on a bracket 410 fixed to and extending from the 80 motor frame. Loosely mounted on shaft 413 is a worm wheel 416, which rests upon a bearing bracket 417, fixed to and extending outwardly from the motor housing 399. A clutch jaw 418 is fixed to the hub of the worm wheel 85 416. A cooperating clutch jaw 419 is slideable on, but rotatable with, a shaft 413 and is rotatively supported by a bracket 420 fixed to and extending from the motor housing. The shaft is held against upward displacement by a pin and washer 421.

A suitable actuating lever 422 is provided for throwing the clutch mechanism into and out of engagement. Meshing with worm wheel 416 is a worm 423, fixed on the shaft 90 424 of the motor. Thus by operating the clutch 418, 419 the motor will operate the gearing just described and will be swung horizontally to the right or to the left as desired, and thereby the kerf cutter will advance in an arcuate path in either direction to cut the kerf.

Referring now to the present embodiment of the kerf cutting mechanism and the means for driving it, a supporting housing 433 extends outwardly from the forward end of the motor housing 399, and bolted on the top thereof is the cutter bar 434. The cutter bar may be of any suitable or known construction, and is shown provided with a cutter chain 100 435. The cutter chain 435 runs in suitable guides on the cutter bar, and runs over and is driven by a sprocket wheel 436, fixed on a shaft 437, which shaft is journaled in the housing 433. 110

Mounted on shaft 437 to slide therealong, but to rotate therewith, is a clutch jaw 441, movable into and out of engagement with a clutch jaw 442, which is formed on the hub of a bevel gear 443, mounted loosely on the shaft 437. Meshing with the gear wheel 443 is a bevel pinion 444 fixed on the shaft of the motor. Thus the motor and cutter will swing together relatively to the auxiliary frame in either direction, and at the height or angle desired. The kerf may also be cut at the very top of the vein if desired, as the cutter bar is at the top of the mechanism.

The invention in its broader aspects is not limited to the specific mechanism shown and 130

described but departures may be made therefrom within the scope of the accompanying claims without departing from the principles of the invention and without sacrificing 5 its chief advantages.

What I claim is:—

1. A mining machine including in combination traction means the ground engaging base of which is variable in length, a kerf 10 cutter, a driving motor therefor, a support for the cutter and motor movable relatively to the traction means to positions determined by the variations in length of the ground engaging base of the traction means, to vary the 15 vertical location of the kerf in the vein, and means for moving the kerf cutter relatively to the body of the machine to cut a kerf.

2. A mining machine including in combination traction means at either side of the 20 machine, means for driving the traction means at different rates for travelling and steering the machine, the ground engaging base of the traction means being variable in length, a kerf cutter, a driving motor therefor, a support for the cutter and motor movable relatively to the traction means to positions determined by the variations in length of the ground engaging base of the traction means, to vary the 25 vertical location of the kerf in the vein, and means for moving the cutter, while the traction means are at rest, to cut a kerf.

3. A mining machine including in combination traction means the ground engaging 35 base of which is variable in length, a kerf cutter, a driving motor therefor, a support for the cutter and motor movable relatively to the traction means to positions determined by the variations in length of the ground 40 engaging base of the traction means, to vary the vertical location of the kerf in the vein and motor driven means for moving the support.

4. A mining machine including in combination traction means at either side of the 45 machine, means for driving the traction means at different rates for travelling and steering the machine, the ground engaging base of the traction means being variable in length, a kerf cutter, a driving motor therefor, and a support for the cutter and motor 50 variably positionable relatively to the traction means to vary the location of the kerf in the vein.

5. A mining machine including in combination traction means the ground engaging 55 base of which is variable in length, a kerf cutter, a driving motor therefor, a support for the cutter and motor variably inclinable relatively to the traction means to vary the 60 location of the kerf in the vein and a second motor for causing the inclination of the first motor and its cutter.

6. A mining machine including in combination dirigible traction means, a kerf cutter, a driving motor therefor, a support for 65

the cutter and motor movable relatively to the traction means to vary the vertical location of the kerf in the vein a second motor for driving the traction means at different rates, and for causing said movement of the 70 cutter and its motor.

7. A mining machine including in combination traction means having a ground engaging base which is variable in length, a kerf cutter, a driving motor therefor, a support 75 for the cutter and motor movable relatively to the traction means to positions dependent upon the length of said ground engaging base, to vary the vertical location of the kerf in the vein, and means for differently 80 driving different members of the traction means to control the movements of the machine.

8. A mining machine including in combination endless belt traction devices having a 85 ground engaging base variable in length, for traveling the machine, a kerf cutter, a driving motor therefor, a support for the cutter and its motor movable relatively to the traction means to vary the vertical location of 90 the kerf in the vein.

9. A mining machine including in combination endless belt traction devices having a ground engaging base variable in length, for traveling the machine, a kerf cutter, a driving motor therefor, a support for the cutter and its motor movable relatively to the traction means to positions dependent upon the 95 length of said ground engaging base, to vary the vertical location of the kerf in the vein 100 and means for selectively operating the traction belts.

10. A mining machine including in combination endless traction devices having a ground engaging base variable in length, for traveling the machine, a kerf cutter, a driving motor therefor, a support for the cutter and its motor variably inclinable about a horizontal axis to vary the location of the 105 kerf in the vein. 110

11. A mining machine including in combination traction devices in which the same elements serve both to support the weight of the machine and to propel the machine, a kerf cutter, a driving motor therefor, and means including devices acting upon the traction devices for varying the ground engaging base thereof for vertically moving the kerf cutter and motor to vary the vertical location of the kerf in the vein. 115 120

12. A mining machine including in combination traction devices in which the same elements serve both to support the weight of the machine and to propel the machine, a kerf cutter, a driving motor therefor, and means including devices acting upon the traction devices to raise and lower them for moving the kerf cutter and motor to vary the location of the kerf in the vein. 125

13. A mining machine including in com- 130

- bination traction devices in which the same elements serve both to support the weight of the machine and to propel the machine, a kerf cutter, a driving motor therefor, and means including devices acting upon the traction devices for varying the ground engaging base thereof for moving the kerf cutter and motor to vary the location of the kerf in the vein. 5
- 10 14. A mining machine including in combination traction devices in which the same elements serve both to support the weight of the machine and to propel the machine, a kerf cutter, a driving motor therefor, and means including devices acting upon the traction devices to raise and lower them for moving the kerf cutter and motor to vary the location of the kerf in the vein. 15
- 20 15. A mining machine including in combination traction devices in which the same elements serve both to support the weight of the machine and to propel the machine, a kerf cutter, a driving motor therefor, and means including devices acting upon the traction devices for variably inclining the kerf cutter and motor about a horizontal axis to vary the relative location of the kerf in the vein. 25
- 30 16. A mining machine including in combination traction devices in which the same elements serve both to support the weight of the machine and to propel the machine, a kerf cutter, a driving motor therefor, and means including devices acting selectively upon the traction devices for variably inclining the kerf cutter and motor about a horizontal axis to vary the relative location of the kerf in the vein. 35
- 40 17. A mining machine including in combination traction devices in which the same elements serve both to support the weight of the machine and to propel the machine, a kerf cutter, a driving motor therefor, and means including devices acting upon the traction devices for varying the ground engaging base thereof for moving the kerf cutter and motor to vary the location of the kerf in the vein, and means for moving the kerf cutter relatively to the machine to cut a kerf. 45
- 50 18. A mining machine including in combination traction devices in which the same elements serve both to support the weight of the machine and to propel the machine, a kerf cutter, a driving motor therefor, means including devices for moving upon the traction devices and thereby moving the kerf cutter and motor to vary the location of the kerf in the vein, and means for moving the kerf cutter relatively to the machine to cut a kerf. 55
- 60 19. A mining machine including in combination traction devices in which the same elements serve both to support the weight of the machine and to propel the machine, a kerf cutter, a driving motor therefor, means in- 65
- cluding devices acting upon the traction devices for variably inclining the kerf cutter and motor about a horizontal axis to vary the relative location of the kerf in the vein, and means for moving the kerf cutter relatively to the machine to cut a kerf. 70
20. A mining machine including in combination a frame, a kerf cutter, traction means, and motor driven means including devices for varying the ground engaging base of the traction means for variably positioning the kerf cutter to vary the location of the kerf in the vein. 75
21. A mining machine including in combination a frame, a kerf cutter, endless belt traction means, means including devices for changing the vertical extent of the traction means for variably positioning the kerf cutter to vary the location of the kerf in the vein, and means for moving the cutter relatively to the traction means to cut a kerf. 80
22. A mining machine including in combination a frame, a kerf cutter, an endless traction tread at either side of the machine, and means including devices for varying the ground engaging base of the traction treads for variably positioning the kerf cutter to vary the position of the kerf in the vein. 85
23. A mining machine including in combination a frame, a kerf cutter, an endless traction tread at either side of the machine, means including devices for varying the reaches of the traction treads for variably positioning the kerf cutter to vary the position of the kerf in the vein and means for selectively driving the traction treads. 90
24. A mining machine including in combination a frame, a kerf cutter, an endless traction tread at either side of the machine, means including devices acting on the traction treads to vary the ground engaging extent thereof, for variably positioning the kerf cutter to vary the position of the kerf in the vein, and means for moving the kerf cutter relatively to the traction treads to cut a kerf. 100
25. A mining machine including in combination a frame, a kerf cutter, endless traction treads, and means acting to vary the ground engaging extent of the treads to raise and lower the kerf cutter to vary the height of the kerf. 105
26. A mining machine including in combination a frame, a kerf cutter, endless traction treads, and means acting to vary the length of the horizontal reaches of the treads to variably position the kerf cutter to vary the position of the kerf. 110
27. A mining machine including in combination a frame, a kerf cutter, endless traction treads, and means for varying the height of the treads to raise and lower the kerf cutter to vary the height of the kerf. 115
28. A mining machine including in combi- 120
- 125

nation a frame, a kerf cutter, endless traction treads, and means for varying the height of the treads to variably position the kerf cutter to vary the position of the kerf.

5 29. A mining machine including in combination a frame, traction means variable in length horizontally thereof, carried by the frame, cutting means variably positionable with respect to the frame, and means cooperating with the traction means and the cutting means whereby the positioning of the one controls the positioning of the other.

10 30. A mining machine including in combination a frame, traction means the effective 15 ground engaging portion of which is variable in length, cutting means variably positionable with respect to the frame, and means cooperating with the traction means and the cutting means, whereby varying the ground 20 engaging length of the traction means controls the positioning of the cutting means.

25 31. A mining machine including in combination a frame, traction means carried by the frame and movable with respect thereto, cutting means and a motor therefor movable together as a unit with respect to the frame, and means, controlled by the positioning of the traction means, for controlling the positioning of the cutting means and its motor.

30 32. A mining machine including in combination a frame, traction means variable in length horizontally thereof, carried by the frame, cutting means and a motor therefor both variably positionable with respect to the 35 frame, and means cooperating with the traction means and the cutting means and motor whereby the positioning of the one controls the positioning of the other.

35 33. A mining machine including in combination a frame, traction means the effective 40 ground engaging portion of which is variable in length, cutting means and a driving motor therefor variably positionable together with respect to the frame, and means cooperating with the traction means and the cutting means, whereby varying the ground engaging length of the traction means controls the positioning of the cutting means and its motor.

45 34. A mining machine including in combination a main frame, supporting wheels therefor, an auxiliary frame, variably positionable with respect to the main frame, a kerf cutter carried by the auxiliary frame, and means, connected to the wheels and to the auxiliary movable frame, for simultaneously changing the positions of the wheels and of the auxiliary frame.

50 35. A mining machine including in combination a main frame, traction devices therefor, a motor carried by the main frame, for driving the traction devices, an auxiliary frame, a kerf cutter and a driving motor therefor, carried by the auxiliary frame, and

means, connected to the traction devices and 65 to the auxiliary frame, for controlling the horizontal extent of the traction devices and the vertical placement of the auxiliary frame.

36. A mining machine including in combination a main frame, supporting wheels 70 therefor, an auxiliary frame variably positionable vertically with respect to the main frame, and yoke means, pivotally mounted on the main frame and engageable with the wheels and with the auxiliary frame, for 75 controlling the positioning of the auxiliary frame.

37. A mining machine including in combination a main frame, a propelling motor carried thereby, supporting wheels therefor, 80 an auxiliary frame variably positionable vertically with respect to the main frame, a kerf cutter and a driving motor therefor carried by the auxiliary frame, and yoke means, pivotally mounted on the main frame and engageable with the wheels and with the auxiliary frame, for controlling the positioning of 85 the auxiliary frame.

38. A mining machine including in combination a main frame, supporting wheels 90 therefor, an auxiliary frame variably positionable with respect to the main frame, a kerf cutter carried by the auxiliary frame, and yoke means, pivotally mounted on the main frame and engageable with the auxiliary 95 frame and with the wheels, for varying the lateral placement of the wheels and the vertical placement of the auxiliary frame.

39. A mining machine including in combination a main frame, supporting wheels 100 therefor, an auxiliary frame variably positionable with respect to the main frame, a kerf cutter carried by the auxiliary frame, yoke means, pivotally mounted on the main frame and engageable with the auxiliary frame and with the wheels, for varying the lateral placement of the wheels and the vertical placement of the auxiliary frame, and a motor carried by the main frame and connectable with said yoke means, for effecting the change in positions of the auxiliary frame and wheels. 110

40. A mining machine including in combination a main frame, supporting wheels therefor arranged in pairs, an auxiliary frame, a kerf cutter carried thereby, yoke members carried by the main frame, connected to the auxiliary frame, and interconnecting the two wheels in each pair, and means for moving the yoke members, whereby one wheel of each pair is moved upwardly, while the other wheel of that pair is moved horizontally. 115

41. A mining machine including in combination a main frame, supporting wheels therefor arranged in pairs, an endless traction belt enclosing certain pairs of wheels, an auxiliary frame, a kerf cutter carried thereby, yoke members engageable with re- 125

spective pairs of wheels, the yoke members also being engageable with the main and auxiliary frames, and means for moving the yoke members for variably positioning the auxiliary frame.

42. A mining machine including in combination a main frame, supporting wheels arranged in pairs, an endless traction belt extending around certain pairs of wheels, an auxiliary frame, a kerf cutter carried thereby, yoke members, pivoted to the main frame, engageable with the auxiliary frame and with respective pairs of wheels, and means for moving the yoke members about their pivots for varying the ground engaging base of the traction belt and for variably positioning the auxiliary frame.

43. A mining machine including in combination a main frame, supporting wheels arranged in pairs, an endless traction belt extending around certain pairs of wheels, an auxiliary frame, a kerf cutter carried thereby, a motor for driving the kerf cutter, carried by the auxiliary frame, yoke members, pivoted to the main frame, engageable with the auxiliary frame and with respective pairs of wheels, and means for moving the yoke members about their pivots for varying the ground engaging base of the traction belt and for variably positioning the auxiliary frame.

44. A mining machine including in combination a main frame, supporting wheels arranged in pairs, an endless traction belt extending around certain pairs of wheels, an auxiliary frame, a kerf cutter carried thereby, yoke members, pivoted to the main frame, engageable with the auxiliary frame and with respective pairs of wheels, and means including a motor carried by the main frame for moving the yoke members about their pivots

for varying the ground engaging base of the traction belt and for variably positioning the auxiliary frame.

45. A mining machine including in combination a main frame, supporting wheels arranged in pairs, an endless traction belt extending around certain pairs of wheels, a motor carried by the main frame for driving the traction belt, an auxiliary frame, a kerf cutter carried thereby, a motor for driving the kerf cutter, carried by the auxiliary frame, yoke members pivoted to the main frame, engageable with the auxiliary frame and with respective pairs of wheels, and means including a motor carried by the main frame for moving the yoke members about their pivots for varying the ground engaging base of the traction belt and for variably positioning the auxiliary frame.

46. A mining machine including in combination a frame, a kerf cutter carried thereby, means for supporting the frame, including wheels arranged in pairs, and means acting on a given pair of wheels for raising one of the wheels above the ground level and for raising the frame, while the other wheel remains at the ground level.

47. A mining machine including in combination a kerf cutter carried thereby, means for supporting the frame, including wheels arranged in pairs, a common pivotal mounting for a pair of wheels, and means cooperating with the mounting for the wheels for raising one of the wheels and thereby raising the frame, the other wheel meanwhile remaining substantially at the ground level.

In testimony whereof, I have signed my name to this specification.

KENNETH DAVIS.
